GUY B. BEBOUT, OF WHEELING, WEST VIRGINIA.

WICKET FOR DAMS.

1,184,062.

Specification of Letters Patent. Patented May 23, 1916.

Application filed August 5, 1915. Serial No. 43,792.

To all whom it may concern:

Be it known that I, GUY B. BEBOUT, a citizen of the United States of America, and resident of Wheeling, county of Ohio, and 5 State of West Virginia, have invented certain new and useful Improvements in Wickets for Dams, of which the following is a specification.

This invention relates broadly to improvements in wicket dams, and specifically to a 10 collapsible wicket for such dams.

The primary object of the invention is to provide a novel and improved form of movable dam-section or wicket which may be 15 readily moved from a reclining to an elevated position, and vice versa, irrespective of the pool level or head of water.

Further objects of the invention are to provide a wicket which is self-lowering at 20 predetermined elevations of water in the upper pool, means being thus afforded for automatically regulating the depth of such upper pool; to provide a wicket which may be conveniently connected to and disconnected from the foundation, and thus to materially reduce not only the initial cost, but 25 also the cost of operation and maintenance of movable dams; and to provide a wicket the body of which may be made of reinforced concrete.

In describing the invention in detail, reference is had to the accompanying drawings, forming a part of this specification, in which—

35 Figure 1 is a perspective view of the lower portion of a wicket constructed in accordance with my invention, illustrating the collapsible anchors; Fig. 2 is a detail section showing a preferred hinge connection for 40 the wicket; Fig. 3 is a side elevation of the invention, showing a modified form of hinge connection; Fig. 4 is a front face view of the wicket body with cover plates removed to show the lowering mechanism; Fig. 5 is 45 a substantially central longitudinal section taken through Fig. 4; Figs. 6 and 7 are cross sections taken respectively on lines 6—6 and 7—7, Fig. 5; Fig. 8 is a view similar to Fig. 3, showing a modified form of collapsible or 50 folding anchor; and Fig. 9 is a detail view showing in rear elevation the joint between the members of the anchor shown in Fig. 8.

Referring to said drawings, in which like designating characters distinguish like parts throughout the several views—1 indicates a shutter which may be formed of any appro-

priate material, preferably reinforced concrete, and which is free at both ends, neither of said ends being hinged or otherwise connected to any fixed object. Pivots 60 tally connected to said shutter at a point below the middle thereof is a frame by means of which it may be firmly supported in elevated position, as shown in Figs. 1, 3 and 8. Said frame comprises, essentially, one or 65 more metal props 2, a pair thereof being preferably employed, and one or more metal anchors each of which consists of two members 3 and 4 placed end to end and pivotally connected. Said props have a parallel disposition and are pivotally connected at their upper ends, as to a horizontal rod or shaft 5 mounted in bearings 6 located on the downstream face of the shutter, and are pivotally 70 connected at their lower ends to shoes 7 which rest on a foundation 8, said props thus occupying parallel inclined bracing positions with respect to said shutter when the latter occupies its elevated position. The lower ends of the anchor members 3 are fixed 75 upon a rod or shaft 9 which is journaled in the adjacent ends of a pair of bars 10; and the upper anchor members 4 have their upper ends fixed to the shaft 5. Each member 4 is provided with an extension 11, L-shaped 80 in cross section, one member of which is designed to engage the connected member 3 on its downstream face and thus limit the extension movement of the anchor members, preventing said members, for a purpose 85 which will hereinafter be made apparent, from assuming positions in direct alinement.

The bars 10 in the ends of which the rod or shaft 9 is journaled, as aforesaid, occupy 90 substantially reclining positions upon the foundation 8 and have their opposite ends attached to the shoes 7, as shown in Fig. 1. The opposite ends of the shaft 9 project outward from the bars 10 and are received underneath hook-shaped lugs 12 which are 100 formed on or attached to the downstream side of a metal sill 13 which is disposed transversely of the bed of the stream and is permanently fixed to the foundation 8. Foot-portions 14 or equivalent devices are 105 formed on the under sides of said bars 10 for resting upon the foundation to support the said ends of shaft 9 at a height which will prevent chance disassociation of said shaft from the lugs 12, as is clearly shown in Fig. 110 2, said foot-portions being located at points sufficiently far removed from the connection

of said bars with said shaft that they will not, when the bars are elevated somewhat to an inclined position, interfere with the introduction and removal of said shaft into 5 and out of interlocking engagement with said lugs.

The sill 13 has an upwardly and forwardly inclined portion 15 constituting a seat upon or against which the lower end of 10 the downstream face of the shutter rests or abuts when the latter occupies its elevated position and by which downstream movement of the lower end of the shutter is limited.

15 The wicket is normally maintained in its elevated position, not only by the force of gravity acting on the nearly vertical shutter, but also by the pressure exerted by the impounded water against said shutter. To 20 lower the wicket, either a horizontal force sufficient to overcome the forces maintaining it upright may be applied in a downstream direction to the upper end of the shutter, or a force may be applied in an upstream direction to the lower end of the shutter. 25 In either case said shutter is rotated counter clockwise on the adjacent ends of the props 2 to a point where the said forces tending to maintain the shutter upright are overcome, when, by gravity, the frame collapses, 30 allowing the wicket to assume substantially the lowered position indicated in dotted lines in Fig. 3. As is obvious, when the said forces tending to maintain the shutter upright have been overcome, as above explained, the weight of the shutter and frame causes the anchor members to close in substantially jack-knife fashion, said members turning at their point of pivotal connection 35 and the rods or shafts 6 and 9 to which their ends are connected rotating in their bearings. Due to the fact that said members are prevented from assuming positions in direct alignment, as aforementioned, little or no 40 resistance to a prompt collapse of the anchor is offered when the shutter has been rotated to a point where the force of gravity and the horizontal component of the pressures due to velocity and static head of the water 45 thereagainst tending to hold it upright have been overcome.

While the wicket shutter and supporting frame may, theoretically, be so assembled and proportioned that it will be tripped automatically when the upper pool, or impounded water, reaches a predetermined elevation, it has been found desirable from an administrative standpoint to eliminate all uncertainty by the provision of positively actuated mechanism whereby automatic tripping of the wicket at a predetermined pool elevation is accomplished. Said mechanism comprises, essentially, an auxiliary shutter 16 located in an opening 17 provided in the main shutter 1 below the point

of support of the latter, said auxiliary shutter having trunnions 18 journaled in the main shutter at opposite sides of said opening 17. Said trunnions are located below the middle of said auxiliary shutter and thus 70 below the center of pressure of water to which it may be subjected, so that it normally occupies the open position shown in dotted lines in Fig. 5, permitting water to pass in a substantially unobstructed manner 75 through said opening, thus relieving to a large extent the pressure which tends to maintain the upright position of the main shutter. Said auxiliary shutter is held in upright position closing the opening 17 by 80 means of a spring pressed latch 19 which operates through a casing 20 which is fixed in a recess 21 provided in the downstream face of the main shutter. Said latch is suitably connected to a lever 22 intermediate 85 the ends of the latter, one of said ends being pivoted to said main shutter and the opposite end being pivoted to the lower end of a rod 23 which lies longitudinally of said shutter and has its upper end pivotally connected to a transversely disposed lever 24 intermediate the ends of the latter. Said lever 24 has one end pivotally connected to the main shutter and has an arm 25 on its free end directed forward through a slot 26 in 90 the rear wall of a bucket 27 which is rigidly mounted on the downstream face of the main shutter adjacent to the upper end thereof. Said bucket has its upper end covered by a screen 41 and is adapted to receive water therein when the latter reaches a level where it flows over the top of the shutter 1. Located within said bucket is a float 28 movable on suitable guides 29 and having the arm 25 rigidly attached thereto. Said 95 float has its lower end open and is designed to be elevated by air confined therein when water rises around it.

In practice, when water enters the bucket 27 and rises about the float 28, the latter is 100 caused to rise by the buoyant air confined therein, and, through the intermediate levers actuated by said float, the latch 19 is withdrawn from supporting relation to the auxiliary shutter, which latter immediately 105 swings forward on its trunnions due to unbalanced water pressure, and thus relieves the pressure on the lower end of the main shutter to such an extent that the latter becomes unbalanced and swings *en bascule*, 110 causing the supporting frame therefor to collapse. When the main shutter 1 has assumed the reclining position indicated in dotted lines in Fig. 3, the auxiliary shutter 115 again assumes a position closing the opening 17; and, the air having been permitted to escape from the open ended float 28, the latch is again projected into supporting relation to said auxiliary shutter, being actuated by suitable means, as the latch-spring 120

40 and a retractile coil spring 30 interposed between the lower end of the lever 23 and a fixed part of the main shutter. Thus, when the main shutter is again elevated, the auxiliary shutter will be disposed in its upright position.

The various levers described are located in a suitably shaped recess 34 provided therefor in the downstream face of the main shutter 10 and preferably work in heavy grease. A cover plate 35 fitted in said recess serves to protect said levers and to retain the grease.

A small aperture 31 is provided in the bottom of the bucket to permit water carried by the latter when elevated to drain therefrom, as also water deposited in the bucket by waves or during rains.

In Fig. 3 I have illustrated a modified form of hinge connection between the supporting frame and the sill, the modification consisting in dispensing with the hook-shaped lugs 12 shown in Figs. 1 and 2 and substituting openings or sockets 32 in the downstream face of the sill 13^a, and in providing rearwardly extending upturned hooks 33 on the adjacent ends of the bars 10^a, said hooks being designed for introduction in said sockets, as shown.

A modified form of anchor is illustrated in Figs. 8 and 9, the same comprising members 3^a and 4^a the adjacent ends of which have integral forwardly projecting arms 36 connected at their ends by a pivot pin 37. Interengaging lugs 39 and 38 carried by the adjacent faces of said members 4^a and 3^a respectively prevent a forward swinging of member 4^a with respect to member 3^a from their alined positions. Since the point of pivotal connection 37 is located in a forward position with respect to the axis of the members 3^a and 4^a, but slight resistance is offered to the collapse of said members in a manner similar to that of the members 3 and 4 hereinbefore described.

A closed tank 42 may be, and preferably is fixed on the front, or downstream, face of the auxiliary shutter 16 adjacent to the upper edge thereof, the same being adapted for containing air whereby said shutter is rendered sufficiently buoyant that it will automatically swing to closing position when the main shutter is partially elevated from its collapsed position.

What is claimed is—

55 1. A wicket comprising, in combination with a foundation having a sill located in fixed position thereon, a shutter having both ends free, props pivotally connected to said shutter intermediate its ends and adapted to support the same in an elevated position with its lower end seated against the upstream face of said sill, bars resting on and independent of said foundation and detachably connected at one end to said sill, the opposite ends of said bars having piv-

otal connection with the lower ends of said props, and foldable anchors interposed between the upper ends of said props and the upstream ends of said bars.

2. A wicket comprising, in combination with a foundation having a sill located in fixed position thereon, a shutter having both ends free, props pivotally connected to said shutter below the middle thereof and adapted to support said shutter in an elevated position with its lower end seated against the upstream face of said sill, bars resting on and independent of said foundation, said bars having their upstream ends detachably connected to said sill and having the lower ends of said props pivotally connected to their downstream ends, and foldable anchors pivotally connecting the upstream ends of said props to the corresponding ends of said bars whereby the extent of elevation of the former is limited.

3. A wicket comprising, in combination with a foundation having a sill located in fixed position thereon, a shutter having both ends free, props pivotally connected to said shutter below the middle thereof and adapted to support said shutter in an elevated position with its lower end seated against the upstream face of said sill, bars resting on and independent of said foundation, said bars having their upstream ends detachably connected to said sill and having the lower ends of said props pivotally connected to their downstream ends, and anchors connecting the upstream ends of said props to the corresponding ends of said bars whereby the extent of elevation of the former is limited, each of said anchors consisting of a pair of pivotally connected members which lie in substantial alinement when the shutter occupies elevated position and which are collapsible to folded position, the pivotal connection of said members being out of alinement with the connections of the opposite ends of said members.

4. A wicket comprising, in combination with a foundation having a sill located in fixed position thereon, a shutter having both ends free, props pivotally connected to said shutter below the middle thereof and adapted to support said shutter in an elevated position with its lower end seated against the upstream face of said sill, bars resting on and independent of said foundation, said bars having their upstream ends detachably connected to said sill and having the lower ends of said props pivotally connected to their downstream ends, foldable anchors pivotally connecting the upstream ends of said props to the corresponding ends of said bars whereby the extent of elevation of the former is limited, and automatically controlled means for releasing the pressure of water tending to maintain said shutter in elevated position.

5. A wicket comprising, in combination with a foundation having a sill located in fixed position thereon, a shutter having both ends free, props pivotally connected 5 to said shutter below the middle thereof and adapted to support said shutter in an elevated position with its lower end seated against the upstream face of said sill, bars resting on and independent of said foundation, said bars having their upstream ends detachably connected to said sill and having the lower ends of said props pivotally connected to their downstream ends, foldable anchors pivotally connecting the upstream ends of said props to the corresponding ends of said bars whereby the extent of elevation of the former is limited, and automatically controlled means whereby the pressure of impounded water 20 against the lower portion of said shutter is relieved.

6. A wicket comprising, in combination with a foundation having a transversely disposed sill fixed thereon, a shutter having

both ends free, collapsible means pivotally connected to said shutter and normally co-operating with the impounded water for maintaining the same in elevated position with its lower end seated against the upstream face of said sill, said shutter having 30 an opening therethrough adjacent to its lower end, an auxiliary shutter pivotally mounted in said opening for closing the latter, means normally holding said auxiliary shutter in closing position, and means 35 carried by said shutter and adapted to be actuated by the water when a predetermined pool level has been reached whereby said holding means is withdrawn to allow said auxiliary shutter to open, relieving the 40 water pressure tending to hold the main shutter upright.

In testimony whereof, I affix my signature in presence of two subscribing witnesses.

GUY B. BEBOUT.
